UNITED STATES PATENT OFFICE.

EMMANUEL J. ALFIERES, OF NEW YORK, N. Y., ASSIGNOR OF ONE-HALF TO CYRIL DE WYRALL, OF RIDGEFIELD PARK, NEW JERSEY.

VAULT-LIGHT.

1,090,113.

Specification of Letters Patent. Patented Mar. 10, 1914.

Application filed August 20, 1912. Serial No. 716,023.

To all whom it may concern:

Be it known that I, EMMANUEL J. ALFIERES, citizen of the United States, residing at New York, in the county of New York and State of New York, have invented certain new and useful Improvements in Vault-Lights, of which the following is a specification.

This invention relates to vault lights, and has for its object the production of a glass body or lens, and a metal holder therefor, both having special construction and arrangement with respect to each other, the holder being adapted to be embedded in concrete, and the lens being removably secured therein. By the use of this invention the removal of a broken lens and the substitution of a new lens is rendered easy and convenient.

20 In the accompanying drawings setting forth the construction and arrangement of this invention, Figure 1 represents a top plan view of the holder. Fig. 2 is a bottom plan view of the lens. Fig. 3 is a vertical section of the lens and holder assembled, the latter being surrounded by a portion of a cement vault covering.

The same letter refers to the same part in the description and drawings.

30 In Fig. 1 is shown a metal lens holder A, which may be either square, or circular as illustrated. It has one or more encircling ribs B and C, which are usually interrupted by spaces such as space b. The holder A has an upper shoulder D, and a lower lip E. On the inside or rim of the lip E of the holder is an annular, rounded projection or bead e forming part of the lip E. The lens or transparent glass body G, is constructed 35 with an upper flange or shoulder H, and in its bottom, as best shown in Fig. 2, the lens has a circular groove J, and a central cylindrical cavity K. When the parts are assembled as shown in Fig. 3, a gasket F of 40 packing material is placed in groove J and the groove then engages the projection e of the lip E of the holder.

In Figs. 1 and 3, it will be observed that the holder A has a half-round, inwardly 45 projecting vertical rib a, and that the lens G is provided with a groove g constructed to receive the rib a. This engagement takes place when the lens is introduced downwardly into the holder, and its purpose is

to prevent the lens from turning upon its 55 axis when in the holder.

In Figs. 2 and 3 it is illustrated that the lens has a depending portion L, which may extend partly around the lens as shown, or entirely around, and through the depending 60 portion L is passed the locking pin M. It will be noted that the pin is passed through the portion L of lens G from within the cavity K, and beneath the holder A.

The operation of this invention is thought 65 to be readily discernible from the drawings. The lens is introduced from the top and removed the same way. The placing of the pin M in place prevents the displacement of the lens upwardly, and, as the pin is 70 slightly wedge-shaped the lens and packing F and the holder are tightly held together. By driving out the pin, the ends of which are exposed to the action of any convenient tool, the lens is easily removed. 75

What I claim is:—

1. The combination with a lens having a central cavity, the wall of the said cavity having an opening through it, a lens holder having a portion arranged contiguous to 80 the lens exteriorly and above the said opening, and a pin removably inserted in the said opening of the cavity of the lens and projecting outwardly below the said contiguous portion of the lens holder. 85

2. The combination with a lens having a central cavity, the wall of the said cavity having an opening through it, a lens holder provided with external projecting portions and having an internal portion arranged 90 contiguous to the exterior of the lens and above the said opening, and a pin removably inserted in the said opening in the wall of the lens and projecting outwardly below the said contiguous portion of the lens 95 holder.

3. The combination with a lens holder, of a lens having a central cavity, the wall of the said cavity of the lens extending below the lower surface of the holder and having 100 an opening through it, and a pin removably inserted in the said opening and projecting outwardly below the holder.

4. A vault light comprising a holder having an upper shoulder and a lower lip, and 105 a lens having an upper shoulder engaging the said shoulder of the holder, the said lens having an annular groove engaging the

lip of the holder, the said lens having a cavity opening from the bottom of the lens, the wall of the said cavity having an opening through it, and a pin removably placed in the said opening and projecting outwardly beyond the lens and below the holder.

5. A vault light comprising a holder having an upper shoulder and a lower lip, the said lip having a vertical projection, and
10 a lens having an upper shoulder engaging the said shoulder of the holder, the said lens having a lower portion arranged adjacent to the lip of the holder, the said lens having a vertical groove engaging the said

vertical projection of the holder, the said lens having a cavity opening from the bottom of the lens, the wall of the said cavity having an opening through it, and a pin removably placed in the said opening and projecting outwardly beyond the lens and 20 below the holder.

In testimony whereof I affix my signature in presence of two witnesses.

EMMANUEL J. ALFIERES.
